OUTBOARD MOTOR CARRIER

Vivian L. Ott, Norfolk, Va.

Application March 21, 1958, Serial No. 50,137

Term of patent 14 years

(Cl. D14—3)

I claim:

The ornamental design for an outboard motor carrier, as shown and described.
